UNITED STATES PATENT OFFICE

2,678,632

AUTOMATIC CATTLE OILER

William E. Brown, Spearman, Tex.

Application July 28, 1952, Serial No. 301,347

7 Claims. (Cl. 119—157)

1

This invention relates to new and useful improvements and structural refinements in apparatus for oiling cattle, particularly hogs, and the principal object of the invention is to provide a device of the character herein described, whereby hogs and cattle may be efficiently and automatically oiled by simply coming in contact with certain actuating elements with which the device is equipped.

Some of the advantages of the invention reside in its simplicity of construction, in its efficient and dependable operation and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a perspective view of the invention in use;

Figure 2 is a vertical sectional view of the invention, the same being taken substantially in the plane of the line 2—2 in Figure 3;

Figure 3 is a transverse cross-sectional view, taken substantially in the plane of the line 3—3 in Figure 2;

Figure 4 is an enlarged fragmentary elevational detail of the fulcrum means used in the invention, and

Figure 5 is an enlarged fragmentary sectional detail, taken substantially in the plane of the line 5—5 in Figure 1.

Like characters of reference are employed to designate like parts in the specification and throughout the several views.

Referring now to the accompanying drawings in detail, the invention consists of an automatic cattle oiler which is designated generally by the reference character 10 and embodies in its construction a supporting frame 12 including an elongated base portion 14 and a plurality of upwardly extending rods 16, the base portion 14 being equipped with a plurality of sockets 18 in which the lower ends of the rods 16 are removably positioned, so that the frame may be readily disassembled when the apparatus is not in use.

A horizontally elongated, cylindrical tank 20 is mounted in an elevated position on the frame 12, this being achieved by providing the bottom portion of the tank with suitable sockets 22 to receive upper end portions of the rods 16, the tank 20 also being equipped at the top thereof

2

with a removable cover 28 which is sustained in position by suitable studs 22 having nut members 24. These nut members are formed integrally with substantially tubular guides 26, the purpose of which will be hereinafter described.

The tank 20 is adapted to receive a quantity of oil or some other suitable liquid, the normal level of which is indicated at 28, and if desired, the cover 28a may be provided with a hinged man hole 30 so that the level of liquid in the tank may be observed and the supply thereof replenished, when so desired.

The end walls of the tank are provided with vertically elongated slots 32 and bearing blocks 34 are secured to the tank at the opposite sides of the slots to accommodate fulcrum pins 36. These fulcrum pins, in the nature of trunnions are provided intermediate the ends of a pair of tubes 38 which extend through the slots 32 into the tank and terminate at their inner ends in scoops 40.

The outer ends of the tubes 38 are closed but are provided with relatively small outlet apertures 42. A tension spring 44, passing freely through the aforementioned guides 26, has the ends thereof suitably anchored to the outer ends of the tubes 38, whereby the outer ends of the tubes are urged upwardly, as shown in Figure 2. However, flexible elements 46, in the nature of cables or ropes, are also anchored to the outer ends of the tubes and extend downwardly therefrom, having their lower ends connected at 46a to the ends of the base 14.

When the invention is placed in use, the tubes 38, particularly the outer ends thereof, are normally urged upwardly by the spring 44, in which position the scoops 40 are submerged in the liquid in the tank. However, when an animal comes in rubbing contact with the element 46 as shown in Figure 1, the associated tube is drawn downwardly and the oil picked up by the scoop 40 is passed through the tube and discharges through the associated aperture 42 on the animal's body, thus effecting the oiling operation.

It is believed that the advantages and use of the invention will be readily understood from the foregoing disclosure and therefore, further description thereof at this point is deemed unnecessary.

While in the foregoing there has been shown and described the preferred embodiment of this invention it is to be understood that minor changes in the details of construction, combination and arrangement of parts may be resorted

to without departing from the spirit and scope of the invention as claimed.

Having described the invention, what is claimed as new is:

1. A cattle oiler comprising a supporting frame, an elongated tank mounted thereon and adapted to contain a quantity of liquid, said tank having an end wall provided with an opening above the normal level of liquid therein, a tube extending through said opening and pivoted intermediate the ends thereof to said tank, said tube being swingable in a vertical plane, a liquid scoop provided at the inner end of said tube, the outer end of the tube being provided with a liquid outlet aperture, and a flexible element extending from the outer end of said tube downwardly to said frame, and a resilient element operatively connected to the outer end of said tube and said tank to urge the outer end of the tube upwardly to tension said flexible element.

2. A cattle oiler comprising a supporting frame, a tank mounted on said frame intermediate the ends of said frame, said tank being provided with an aperture intermediate the top and bottom, said aperture opening into one of the ends of said frame, an elongated liquid dispensing element having one end portion projecting forwardly from said one end of said tank through said aperture and having its other end portion disposed within said tank for swinging movement entirely within the tank, said element being pivoted to said tank intermediate its ends, resilient means operatively interconnecting said one end of said element and said tank and urging said one end upwardly and said other end toward the bottom of the tank, and a flexible element connecting said one end of said element to said frame whereby an animal rubbing thereagainst will tilt said one end of said element downwardly over the body of the animal to dispense liquid from the tank thereon.

3. The combination of claim 2 wherein said liquid dispensing element comprises a tube having a liquid scoop at said other end.

4. A cattle oiler comprising a supporting frame, an elongated liquid carrying tank mounted on said frame intermediate the ends of said frame, said tank having openings in the ends thereof, an elongated liquid dispensing element pivotally mounted on each end of said tank and having an inner end disposed within said tank and an outer end disposed exteriorly of said tank, resilient means mounted on said tank operatively connected to the outer end of each liquid dis-

pensing element and urging the same upwardly, a flexible member connecting each outer end to an end of said frame whereby flexure of each flexible member by an animal causes the outer end of each liquid dispensing element to tilt downwardly in opposition to the resilient means to pour liquid over the animal.

5. The combination of claim 4 wherein said resilient means includes a coil spring extending over the top of said tank, guides on said tank guidingly receiving the intermediate portions of said spring.

6. A cattle oiler comprising a supporting frame, a liquid containing drum mounted horizontally on said supporting frame, elongated liquid dispensing elements pivotally mounted on the ends of said drum intermediate their ends, said elements being pivoted about a horizontal axis perpendicular to the longitudinal axis of said drum, said elements having inner end portions disposed within said drum and outer end portions projecting exteriorly through the ends of said drum, resilient means extending longitudinally along the top of the drum, guide means on the top of said drum slidingly retaining said resilient means thereon, said resilient means having end portions connected to the outer end portions of said dispensing elements urging said outer end portions upwardly, flexible rubbing elements connecting the outer end portions of said dispensing elements and said supporting frame for swinging said outer end portions downwardly against the action of said resilient means when cattle rub thereagainst, liquid scooping means on the inner ends of said dispensing elements lifting liquid from the drum into the dispensing elements as cattle rub against the flexible elements.

7. The combination of claim 6 wherein said dispensing elements are pivoted to said drums substantially medially of their lengths.
